UNITED STATES PATENT OFFICE.

HAROLD W. E. JOSLING, OF WESTMINSTER, LONDON, ENGLAND, ASSIGNOR TO
"PERFECTA" BOILER CIRCULATOR LIMITED, OF WESTMINSTER, ENGLAND.

MEANS FOR PROMOTING CIRCULATION OF THE FLUID IN STEAM-GENERATORS.

1,278,478.

Specification of Letters Patent. Patented Sept. 10, 1918.

Application filed April 4, 1918. Serial No. 226,701.

To all whom it may concern:

Be it known that I, HAROLD WILLIAM ED-
WIN JOSLING, of 39 Victoria street, Westmin-
ster, in the county of London, England,
5 have invented certain new and useful Im-
proved Means for Promoting Circulation of
the Fluid in Steam-Generators of the Lan-
cashire Type and other Tubular Heating
Apparatus; and I do hereby declare the fol-
10 lowing to be a full, clear, and exact descrip-
tion of the invention, such as will enable
others skilled in the art to which it apper-
tains to make and use the same.

This invention relates to means for pro-
15 moting the circulation of fluids in steam
generators and other tubular heating appa-
ratus, and applies more particularly to boil-
ers of the Lancashire type. The invention
is not, however, restricted to Lancashire
20 boilers, but is applicable to other boilers
such as, for instance, marine boilers.

Means for promoting the longitudinal cir-
culation of water in steam boilers of the
above type have been proposed, such circu-
25 lating means consisting of a hood, casing or
the like fixed at a suitable height above the
boiler flues the said hood or casing sloping
upwardly toward the back end of the boiler
and having depending sides or wing por-
30 tions which extend down between the out-
sides of the boiler flues and the adjacent
sides of the boiler barrel; further such hood
or casing has been provided with a back
plate adjacent the front or fire door end of
35 the boiler such back plate extending down to
about the horizontal center line of the boiler
flues.

It has been found that the circulation set
up by the above mentioned known means for
40 promoting circulation does not reach the
back end of a boiler, such as a Lancashire
boiler, the length of which is, for instance,
about thirty feet and the diameter about
seven or eight feet, the circulation set up in
45 such a boiler being good for about three-
quarters of its length.

This invention has for its object to pro-
vide improved circulating apparatus of the
general type above mentioned, the apparatus

according to this invention being however 50
so constructed that or provided with means
whereby efficient movement or circulation of
the water from one end of the boiler to the
other with efficient return flow from the back
55 end of the boiler to the circulator or the front
end of the boiler is obtained and main-
tained, efficient provision being made for
the return flow with the result that the fluid
does not have a tendency to "pile up" or to
be checked at the far or back end of the
boiler.

Further according to this invention an in-
clined hood, casing or cover plate is fixed
over the boiler flues at the furnaces for the
purpose of setting up and maintaining lon-
gitudinal circulation, this hood or casing being
provided with a back plate which ex-
tends down to or approximately to the center
line of the flues; one side of this hood or
casing, at its forward or outlet end, is 65
blanked off or closed to a suitable extent by
a plate, hereinafter referred to as a "blank-
ing-off" plate, and the said hood or casing
is also provided along its sides or edges
with depending plates or wings which ex-
70 tend down between the outsides of the boiler
flues and the adjacent sides or walls of the
boiler, the wing or depending plate at the
blanked-off or closed side of the hood being
75 deeper or extending farther down in the
boiler than the depending wing or plate at
the opposite side of the hood or casing
which shallower wing or plate is completely
open at the forward or outlet end of the
80 hood. It will therefore be understood that
the forward or outlet end of the circulator
hood is completely open with the exception
of the portion closed or blanked off by the
above mentioned blanking-off plate. Further
85 according to this invention, in addition to
the above mentioned blanking-off plate an-
other plate, hereinafter called a "deflector
plate", is preferably provided, at the
blanked off side of the hood, which de-
90 flector plate extends forwardly to a suit-
able distance from the outlet end of the hood
or circulator, this deflector plate sloping at a
suitable angle toward the longitudinal center
95

line of the boiler. This deflector plate may form an extension of or may be attached to the aforesaid blanking off plate.

Further in the preferred embodiment of 5 this invention the above mentioned depending side wings or plates form continuations of and extend down in a curve from the flat or approximately flat and upwardly inclined top portion of the hood or casing, so that 10 all objectionable angles are eliminated and the formation of eddies is thus prevented.

In order that the invention may be more readily understood and carried into effect reference is made to the accompanying 15 drawings in which,—

Figure 1 is an end view of a circulator, according to this invention, as applied to a boiler of the Lancashire type.

Fig. 2 is a longitudinal elevation and Fig. 20 3 a plan of the circulator.

Fig. 4 is a plan view of the boiler fitted with circulating apparatus according to this invention but with the upper part of the boiler barrel omitted.

25 Like reference numbers indicate corresponding parts in the several figures of the drawings.

1 is the barrel of the boiler, and 2 are the boiler flues. On the furnace ends of the 30 flues 2 is mounted the circulator which consists of a hood or casing partially surrounding and common to both flues; as shown the top or central portion 3 of the circulator is flat or approximately flat and the depending side portions or wings 4 and 5 are curved 35 downwardly from the edges of the portion 3; further, as clearly shown in Figs. 1 and 2, the depending side or wing 5 at one side of the circulator is deeper and consequently 40 extends farther down in the boiler space, between the flue 2 and the adjacent wall or side of the boiler, than the depending side or wing 4 which, as shown in Fig. 1, terminates with its lower end or edge above 45 the horizontal center of the flues 2. Where the construction of the boiler permits the side wing 5 would preferably be made to extend well below the center line of the flues. It will be understood that in any case the 50 side wing 4 should be made of less depth than the wing 5.

As shown in Fig. 2 the hood or casing slopes upwardly from its end adjacent the furnace doors to its forward or outlet end.

55 6 is the back plate of the circulator which plate as shown extends down between the flues 2 and also extends down on the outside of the flues and thus closes the rear end of the circulator including the rear ends of 60 the side wings 4 and 5. The plates of which the hood or circulator,—including the side wings,—is formed are suitably curved at the rear end as indicated at 6^a, Figs. 2 and 3, and the back plate 6 is suitably secured to

this curved end for instance by means of a 65 flat bar or strap, or bars or straps 7 and bolts and nuts 8 the bars or straps being suitably curved to correspond with the form of the hood or circulator at its rear end.

9 is the hereinbefore mentioned blanking-off plate which as shown partially closes the forward or outlet end of the circulator hood at the deeper side wing 5. As shown in Fig. 1 this plate 9 extends only a short distance down the side wing 5 the portion 75 of which below the edge 9^a of the plate is open at the front. The plate 9 might be made to extend farther down and thus increase the closure of the wing 5 at the front; tests have however demonstrated that with 80 the plate 9 terminating with its lower edge 9^a at or approximately at the position shown in Fig. 1 good results are obtained.

10 is the hereinbefore mentioned deflector plate which, in the example shown, is secured by bolts and nuts to an off-set portion or flange 10^a of the plate 9. This deflector plate extends forwardly from the outlet end of the circulator to any suitable distance toward the far end of the boiler. Tests have however demonstrated that for a boiler about thirty feet long good results are obtained with a deflector plate which extends for a distance of about three to five feet from the outlet end of the circulator, and 95 which is set at the angle or approximately at the angle shown. The plate 10 might however be set at some other suitable angle depending upon the length of the boiler. The deflector plate 10 is, as hereinbefore 100 mentioned, provided for the purpose of insuring effective direction of the water issuing from the outlet end of the circulator diagonally toward the side and end of the boiler opposite to that at or near which the 105 deeper side wing 5 and blanking-off plate 9 are situated.

The hood or circulator is supported on the boiler flues 2 by suitable frames or supports. As shown there are two frames or 110 supports built up of iron or steel bars 11, 11^a and 12, 12^a suitably formed and secured together, and to which the plates of which the hood or circulator is formed are suitably secured for instance as shown by bolts and nuts 13, 13^a the latter (13^a) acting as tie rods or stays which together with the bars 11, 11^a and 12, 12^a support the hood or circulator on the flues 2. The plates 3 forming the top or central portion of the circulator are secured to the outer or curved plates which are carried down to form the depending sides or wings 4 and 5 and to the bars 11 and 12^a of the above-mentioned supporting frames by means of the box nuts 14 120 screwed on to the upper ends of the tie rods or bolts 13^a which project through holes in the outer plates 3.

15 are handles suitably secured to the top or central portion of the circulator which portion is readily removable as a whole by unscrewing the box nuts 14 from the tie 5 rods or bolts 13^a.

As shown the bars 11 and 11^a are secured together at their lower ends by bolts and nuts 16 these bolts being provided at their inner ends with flat heads or plates 16^a 10 which are riveted or bolted to the laterally projecting portions 11^b of the bars 11^a.

17 are the chains or cables by which the circulator is held in position on the flues 2 the ends of the said chains or cables being 15 connected, for instance by hooks and eyes, to the above-mentioned supporting frames. As shown the ends of the cables 17 (Fig. 1) are connected to the parts 11^b of the bars 11^a. 18 is an ordinary screw coupling by 20 which the cables or chains 17 can be adjusted. 19 are bolts securing the central plate 3 to the plates 3 on either side of the said central plate.

In constructing a circulator according to 25 this invention the plates of which it is built are preferably made of such width that they can be readily passed through the manhole of the boiler, and the plates may be provided with slotted bolt holes so 30 that plates of the same size may be used for boilers of various diameters.

The provision of the hereinbefore mentioned blanking off piece or plate 9, which to a suitable extent closes the front or outer 35 let end of the circulator hood or casing at one side thereof, causes the outward flow of water to take place mainly or wholly along one side of the boiler toward the back or far end thereof whence the water re- 40 turns along the opposite side and along the bottom of the boiler to the circulator, the said blanking-off piece preventing outward flow of the water taking place along the side of the boiler at or near which the 45 blanking-off piece is situated and conse- quently enabling efficient return flow to take place from the far end of the boiler to the circulator, the main return flow of water from the far end of the boiler to the circ- 50 ular however taking place, as in known circulating apparatus, along the bottom of the boiler or below the boiler flues. In order to assist the return flow from the far end of the boiler to the circulator the hereinbefore mentioned deeper depending plate or side wing 5 is provided at that side of the circulator hood or casing which is blanked off or closed at the outlet end as above mentioned. Further to insure effec- 55 tive outward flow of the water along one side of the boiler as above mentioned the deflector plate 10 is also provided.

The arrows in Fig. 4 of the drawings show approximately the course taken by

the water in its outward flow from the circulator along one side of the boiler to the far end thereof, and also show approximately the course taken by the water in its return flow from the far end of the boiler to the circulator this return flow taking 70 place, as shown by the arrows, along that side of the boiler at or near which the deeper side wing and the blanking-off plate of the circulator are situated and also, as hereinbefore mentioned, along the bottom 75 of the boiler or below the boiler flues.

The details of construction of the apparatus as hereinbefore described with reference to and shown in the drawings might be varied without departing from the main 80 features of the invention.

Apparatus according to this invention, in addition to being applicable to boilers other than Lancashire boilers, is also applicable for promoting circulation of liquids or 85 fluids in chemical industries.

What I claim as my invention and desire to secure by Letters Patent is:—

1. The combination, with two boiler fire flues arranged side by side, of a circulating 90 device comprising a plate extending over both flues and having downwardly projecting wings of unequal depth at its sides, a deflector secured at the outlet end of the device adjacent to the deeper wing and 95 operating to cause the water when heated to flow diagonally over the flues, and a plate extending crosswise of the flues at the other end of the device.

2. The combination, with two boiler fire 100 flues arranged side by side, of a circulating device comprising a plate extending over both flues and having downwardly projecting wings at its sides, a plate partially closing the outlet end of the device and ar- 105 ranged adjacent to one wing and over one flue and operating to cause the water when heated to flow diagonally over the flues, and a plate extending crosswise of the flues and substantially closing the other end of 110 the device.

3. The combination, with two boiler fire flues arranged side by side, of a circulating 115 device comprising a plate extending over both flues and having downwardly projecting wings at its sides, a plate extending crosswise of and partially over one flue and secured adjacent to one of the said wings at the outlet end of the device, a deflecting plate secured to the last said plate and ar- 120 ranged diagonally over the said flue, and a plate extending crosswise of the flues and substantially closing the other end of the device.

4. The combination, with two boiler fire 125 flues arranged side by side, of a circulating device comprising a plate extending over both flues and having downwardly project-

4
ing wings of unequal depth at its sides, a deflector secured at the outlet end of the device adjacent to the deeper wing and operating to cause the water when heated 5 to flow diagonally over the flues, and a plate extending crosswise of the flues at the other end of the device between the said wings and having a central portion which projects

downwardly in the water space between the two flues. 10

In testimony whereof I have affixed my signature, in presence of two witnesses.

H. W. E. JOSLING.
